UNITED STATES PATENT OFFICE

2,207,863

TENSION DEVICE

Harold Wood Hitchcock, Apponaug, R. I., assignor to Universal Winding Company, Cranston, R. I., a corporation of Massachusetts

Application January 19, 1939, Serial No. 251,816

14 Claims. (Cl. 242—150)

This invention relates to improvements in devices for tensioning a strand of yarn, thread or the like during its delivery to a winding machine, or in other transfer processes, and particularly to means for controlling the amount or degree of tension applied to the strand in accordance with its linear speed or rate of draft.

In the following specification and claims the term "yarn" is employed in a general sense to apply to all kinds of strand materials, either textile or otherwise, and the designation "package" is intended to indicate the product of the winding or like machine whatever its form.

One object of the invention is to provide a differential tension-device adapted to operate automatically to maintain a uniform tension on the yarn during the winding or other operation.

Another object of the invention is to provide controlling means for the tension-device which act positively and accurately to reduce the applied tension on the yarn as the speed of draft of the latter increases whereby to maintain the ultimate tension uniform throughout the winding.

Another object of the invention is to provide controlling means of the type indicated which act positively to control the tension applied to the yarn without the use of springs, weights or other elements liable to cause vibration or chatter of the tension-elements.

Another object of the invention is to provide controlling means of the type indicated which may be minutely and accurately adjusted in accordance with the requirements.

Another object of the invention is to provide controlling means of the type indicated which are adaptable for use with tension-devices of various types having a tension-element movable with respect to another fixed element to vary the degree of tension applied to the strand drawing between the elements.

Another object of the invention is to provide controlling means of the type indicated which are of simple construction, positive and direct in action and proof against derangement or getting out of order.

Further objects of the improvement are set forth in the following specification which describes several preferred embodiments of the invention, by way of example, as illustrated by the accompanying drawings. In the drawings:

Fig. 1 is a side elevation of a conventional type of winding machine in which is incorporated a tension-device for applying tension to the strand of yarn being wound and illustrating the improved controlling means for progressively reliev-

ing the applied tension as the linear speed of the yarn increases during the winding operation;

Fig. 2 is an enlarged part-sectional side elevation of the tension-device and the controlling means therefor showing the position assumed by the parts at the commencement of the winding operation;

Fig. 3 is a view similar to Fig. 2 showing the relationship of the parts at a later stage in the winding operation;

Fig. 4 is a partial plan view of the tension-controlling means;

Fig. 5 is a further enlarged part-sectional side view of the tension-controlling means, indicating diagrammatically the movement imparted to the tension-elements during the progress of the winding operation;

Fig. 6 is a vertical sectional view through the tension-controlling device taken on line 6—6 of Fig. 5 and showing the eccentric mounting for the adjusting means;

Fig. 7 is a vertical sectional view of another form of tension-device adapted to be operated from the improved controlling device;

Fig. 8 is an end view of the tension-device illustrated in Fig. 7;

Fig. 9 is a side view of another modified form of tension-controlling device;

Fig. 10 is a vertical sectional view of the same taken on line 10—10 of Fig. 9;

Fig. 11 is a side view of a modified form of plunger-rod for connecting the tension-elements and controlling means; and

Fig. 12 is a similar view of still another modified form of plunger-rod.

The present invention is concerned particularly with winding machines in which the winding-spindle is rotated at a constant rate of speed so that during the winding of a package thereon the speed of draft or rate of linear movement of the yarn progressively increases with the increase in circumference of the wound mass. It is well known to those skilled in the art that in winding on machines of this type as the winding progresses and the package increases in circumference the yarn must feed thereto at an accelerated rate or with an increasing speed of draft and, therefore, unless controlled, the tension on the running yarn will be augmented or increased from this cause. It has heretofore been proposed to provide means for gradually relieving or reducing the applied tension on the yarn during the growth of the package and the present invention is distinguished from such known devices in that it provides a positive con-

trol of the tension-members rather than through the use of springs, adjustable weights and like unstable elements liable to vibration.

The invention is herein shown as applied to use on a winding machine of conventional type wherein the package is wound on a positively driven winding-spindle and the yarn traversed longitudinally thereof by means of a reciprocating thread-guide. The present improved tension-controlling means is also shown, by way of example, as applied to use with a tension-device of the type illustrated and described in my prior application for Letters Patent, Serial No. 224,386, filed August 11, 1938; but it is to be understood that the invention may be used for controlling the operation of tension-devices of other types wherein the tension-elements are progressively separated, one from the other, or the pressure of one against the other relieved during the winding or like operation.

Fig. 1 of the drawings illustrates a well-known type of winding machine comprising a main frame 2 having upper bearings for a rotary winding-spindle 3 and lower bearings for a cam-shaft 4. Cylindrical or conical packages may be wound on the spindle 3 by traversing the yarn longitudinally thereof through the means of a reciprocating thread-guide 5 which is supported on a swinging frame 6. The thread-guide 5 is connected to a traverse-rod 7 slidable in grooved bearings in the traverse-frame 6 and reciprocated by a helical cam, not herein shown, which is rotated by the cam-shaft 4. The traverse-frame 6 is pivoted on the ends of the cam-shaft 4 to adapt the thread-guide 5 carried thereby to move outwardly away from the winding-spindle 3 as the package is built up thereon. To counterbalance the traverse-frame 6 to maintain the thread-guide 5 bearing against the package the frame is preferably provided with a weighted arm 9 depending therefrom in the manner of a pendulum. As a further means for resisting the action of the package to swing the guide away from the spindle 3, differential pressure-means are employed, but these are not herein shown since they form no part of the present invention.

The tension-device 15 is shown and described in detail in the above mentioned application for United States patent, and is therefore described herein only briefly as relating to the operation of the improved tension-controlling means. Suffice it to state that a pair of concavo-convex disks 16 and 17 are rotatably mounted on a tubular or sleeve-like spindle 18 fixedly held in a hub 19 formed integral with a tension-bracket 20. The bracket 20 has a curved arm 21 which is attached to the side of the winding machine frame 2 by means of screws 22.

60 The tension-disks 16 and 17 are preferably constructed from sheet-metal and formed to substantially saucer-shape with their main radial portions having flat faces adapted to bear against the strand s drawing therebetween. Radially outward beyond their flat portions the tension-disks 16 and 17 are flared laterally in arcuate shape in cross-section and terminate in radial flanges forming flat rims 23 and 24 substantially parallel with their main flat faces.

70 The means for applying pressure to the disks 16 and 17 to force them toward each other to cause them to bear against the strand may consist in a flexible diaphragm 25 for each disk constructed from suitable resilient material such as rubber, fiber or the like. The diaphragms 25 are

of disk-like form, as shown in Fig. 3, and of substantially the same outside diameter as the tension-disks 16 and 17 to adapt them to bear against the rims 23 and 24 of the latter in the manner illustrated in Fig. 2. The diaphragms 25 are formed with axial holes to adapt them to be supported on the central spindle 18 and pressure is applied to the sides of the diaphragms adjacent their centers to cause them to yieldingly press against the outer rims 23 and 24 of the disks 16 and 17.

The tension-device illustrated in Figs. 7 and 8 differs from that described above only in the form of the pressure means employed therewith. In this case the pressure-elements are in the form of spider-like springs 30 slidably arranged on the hollow spindle 18 with the ends of their radial arms bearing against the outer rims 23 and 24 of the tension-disks 16 and 17.

In either case, the diaphragms 25 or the 20 spring-elements 30 are forced toward each other under pressure applied thereto to urge the tension-disks 16 and 17 toward each other to apply resistance to the passage of the yarn drawing therebetween. As shown in Figs. 1, 2 and 3, a 25 preferred form of construction of the pressure means comprises a plunger-rod 33 which is slidable in the axial bore of the hollow spindle 18. The rod 33 projects beyond the outer end of the spindle 18 and is threaded to receive an internally-threaded hub or thimble 34 which is screwed thereon and held in adjusted position by means of a lock-nut 35 screwed onto the threaded extremity of the rod and set up against the hub. The hub or thimble 34 is adapted to engage the 30 side of the outer disk 25, while the inner disk 25 has its central portion bearing against a relatively thin washer 36 abutting the end of the hub 19 in which the spindle 18 is held. The thimble 34 is bored axially at 38 to receive the end of the spindle 18 to adapt it to slide thereon. It will thus be observed that when the plunger-rod 33 is slid to the left, as viewed in Fig. 2, the thimble 34 will bear against the central portion of the outer diaphragm 25 to exert pressure on both diaphragms whereof to cause them to yieldingly press against the rims 23 and 24 of the two disks 16 and 17. As the pressure of the thimble is increased the diaphragms will be flexed to cause them to be bowed inwardly toward each other 50 to a slight extent.

With the form of tension-device shown in Figs. 7 and 8 the spring-elements 30 are flexed in the same manner to cause them to be bowed inwardly toward each other to a slight extent. The inner 55 spring-element 30 may be held against rotation by a pin 40 in the bracket 20 engaging the side of one of the radial arms of the element. Rotation of the outer spring-element 30 is yieldingly resisted by a wire ring 41 frictionally held in a 60 circumferential recess 42 in the thimble 34 and provided with an arm 43 engaging the side of an arm of the element, the ring permitting the outer element to creep or rotate slowly to prevent wearing grooves in the tension-disks 16 and 17. 65 The strand s leads upwardly from a suitable source of supply, passes through a pigtail guide 44 carried by the bracket 20, and across a rod 45 at the upper end of the bracket. From the guiding rod 45 the strand leads across a wire 70 bail 46 and thence through the groove in the thread-guide 5 to the package being wound.

The present invention relates to means for gradually reducing the pressure of the diaphragms 25 or the spring-elements 30, as the case 75

may be, against the disks 16 and 17. This is accomplished by means to be next described which act to slide the plunger-rod 33 longitudinally in the bore of the spindle 18.

5 Screwed into a boss on the arm 21 of the tension-bracket 20 is a stud 49, see Fig. 4, on which is pivotally mounted a bifurcated lever 50. The lever 50 has a hub portion 51 for receiving the stud 49 with arms 52 and 53 radiating therefrom and connected at their ends by a cross-strut 54, see Figs. 4 and 6. The arms 52 and 53 of the lever 50 are provided with alined holes 56 and 57 for receiving the shank portion of an adjusting stud 59. As shown in Fig. 6, the adjusting stud 59 has 10 an eccentric portion 60 with its side abutting the outer face of the arm 52 while its opposite shank end is headed over in the countersunk end of the hole 57 in the arm 53 to hold the stud axially in place and provide frictional resistance to its rotation. An enlarged head 61 formed at the outer end of the stud 59 is slotted to receive a screw-driver to facilitate turning the stud when adjusting the position of the eccentric portion 60 for a purpose to be explained later. The shank of the 15 stud 59 is bored axially to receive the bent end 65 of a wire link 66, see Figs. 4 and 6. The opposite bent end 67 of the link 66 passes through one of a series of holes 68 in a sheet-metal bracket 69 carried by the weighted arm 9 of the traverse-frame 6. The bracket 69 is pivoted on a stud 70 held in a second bracket 71 fastened to the side of the arm 9, see Fig. 1, and forming part of the differential pressure means common to winding machines of the type herein illustrated. The 20 bracket 69 is provided with an arcuate slot 72 through which passes a screw 73 in a threaded hole in the bracket 71 and by loosening the screw 73 the smaller bracket 69 may be adjusted about the stud 70 and thereafter secured in position by tightening the screw. It will be apparent that during the winding operation, as the package increases in diameter the weighted arm 9 is swung in a clockwise direction, as viewed in Fig. 1, and through the bracket 69 and link 66 the lever 50 25 will be rocked about its pivot 49 in a counterclockwise direction.

40 The forward arm 52 of the lever 50 is extended laterally, as indicated at 75 in Fig. 4 and the extension provided adjacent its extremity with a threaded hole for receiving the reduced threaded end of a stud 76. Pivoted on the shank portion 71 of the stud 76 between the extension 75 and head 78 of the stud is a sheet-metal lever 80 provided with a longitudinal slot 81, the sides of which embrace the eccentric portion 60 of the adjusting stud 59. The slot 81 is continued to the right, as viewed in Fig. 5, in a narrower slot 85 to give resiliency to the upper portion of the lever 80 whereby to cause the sides of the slot 81 to exert pressure on the sides of the eccentric portion 60 of the stud 59. In this way the sides of the slot 81 form jaws which engage the eccentric 60 frictionally to resist turning movement of the stud 59. The lever 80 is extended forwardly and laterally in an ear 82 which is provided with a hole 83. The plunger-rod 33, previously described as being slidably mounted in the hollow spindle 18 of the tension-device 15, is bent upwardly at its end and formed with a right-angular portion 84 hooked into the hole 83 of the ear 82 on the lever 80. A preferred form of construction of the tension-controlling device having been described in detail its method of operation will be explained next.

75 To prepare the machine for winding the strand

5 of yarn or the like is drawn upwardly through the guide 44, threaded between the tension-disks 16 and 17, and thence led across the guide 45 and bail 46. The strand is then passed through the thread-guide 5 and its end attached to the tube 7 or other yarn-receiver mounted on the spindle 3. The tension-controlling device, including the levers 50 and 80, is then adjusted angularly about the pivot-stud 49 with the bent end 67 of the link 66 inserted in the appropriate holes 68 in the bracket 69. With the parts of the controlling device thus connected the initial tension on the strand *s* is regulated by adjusting the thimble 34 along the rod 33 to flex the diaphragms 25 or spring-elements 30 to the required degree. That 10 is to say, flexing of the diaphragms adjusts the amount of pressure applied to the rims 23 and 24 of the tension-disks 16 and 17 and thus the initial tension applied to the strand *s* at the start of the winding is regulated in accordance with requirements.

15 The controlling device is further adjusted to regulate the extent of sliding movement imparted to the plunger-rod 33 by the traverse-frame 6 during the winding of a package and thereby the extent to which the applied tension is reduced. Turning the adjusting stud 59 by means of a screw-driver causes its eccentric portion 60 to swing the lever 80 about the pivot-stud 76. With the eccentric portion 60 of the stud 59 in uppermost position, that is, displaced upwardly 90° from the position illustrated in Fig. 2, the hole 83 in the end of the lever 80 will be positioned in axial alinement with the pivot-stud 49. Consequently, as the connected levers 50 and 80 are 20 swung about the pivot 49 under the pulling action of the link 66 during the movement of the traverse-frame 6 no sliding movement will be imparted to the rod 33. To effect movement of the rod 33 and thereby a relief of pressure on the tension 25 disks during the winding the adjusting stud 59 is turned in a clockwise direction, as viewed in Fig. 2, to adjust the connected end 84 of the rod 33 into eccentric relation to the axis of the pivot-stud 49. With the hole 83 adjusted away from the stud 49 in eccentric relation to the axis thereof pivotal movement of the levers 50 and 80 during the winding operation will cause the end 84 of the plunger-rod 33 to swing in an arc concentric with the axis of the stud 49 in the manner 30 of a crank-pin, and thus the rod 33 will be slid toward the right to gradually relieve the pressure of the diaphragms 25 against the rims of the tension-disks 16 and 17.

35 Referring to Fig. 5, the eccentric portion 60 of the adjusting stud 59 is shown as adjusted to lowermost position with the end 84 of the plunger-rod 33 at the maximum distance from the axis of the pivot-stud 49. With this adjustment, when the levers 50 and 80 are swung upwardly in a 40 counterclockwise direction the end 84 of the plunger-rod 33 will be carried therewith in an arc indicated by the line designated *b*. At the start of the winding operation the end 84 of the rod 33 is positioned substantially in a vertical 45 plane of the axis of the stud 49 and at the completion of the winding it will have been moved to the right into the position indicated by the dashed-line circle. During this displacement of its end 84 the rod 33 is moved toward the right a distance 50 equal to that indicated by the reference character *a* and thus the thimble 34 carried by the rod is shifted axially to a corresponding distance to relieve its pressure on the diaphragms 25 or spring-elements 30.

By the above-explained method of operation of the control-device the pressure of the two diaphragms on the tension-disks 16 and 17 is relieved so that the pressure of the disks on the strand 8 drawing therebetween is correspondingly reduced. It will be understood that this relief of the pressure on the diaphragms and the corresponding reduction in the pressure of the tension-disks on the strand is effected gradually and continuously from start to finish of the winding of each package and in proportion to the increase in linear speed or rate of draft of the strand as the package grows in size. In fine, as the speed of draft of the yarn increases due to the growing diameter of the package being wound the applied tension on the yarn is gradually relieved so that the ultimate tension remains substantially constant or uniform throughout the winding. With the present improved construction and arrangement of the tension-controlling means the strand is delivered to the winding machine or other apparatus under substantially uniform tension during variation in its linear speed.

It will be observed by reference to the drawings that as the end 84 of the plunger-rod 33 moves upwardly along the arc b as indicated in Fig. 5 the rod will tilt upwardly slightly. To permit this angular displacement of the rod 33 the axial bore of the spindle 18 is made slightly larger than the diameter of the rod. To avoid this tendency of the rod 33 to be canted in the bore of the spindle 18 the rod may be constructed in two sections as shown in Fig. 11. With this articulated structure of the rod 33 its forward end may terminate in a loop 86 which is pivotally connected to the looped end of a wire link 87 by means of a suitable hinge-pin or stud 88. The opposite bent end 84 of the link 87 is hooked through the hole 83 in the lever 80 and as the lever swings upwardly the link pivots on the pin 88 without tilting the whole rod.

As another means for preventing tilting of the plunger-rod 33 during the pivotal movement of the lever 80 the rod may be provided at its inner end with a vertical loop 90 as shown in Fig. 12. A pin 91 held in the hole 83 of the lever 80 is arranged to project through the loop 90 and as the lever swings upwardly the pin will ride vertically in the loop, thereby imparting longitudinal sliding movement to the rod 33 without tilting it.

Figs. 9 and 10 of the present drawings illustrate a modified form of construction of the invention. In this embodiment a single lever 100 is shown as pivoted on a stud 99 corresponding to the stud 49 previously described. The lever 100 is formed with an arm 101 having a hole at its end through which the bent end 65 of the operating link 66 is hooked. Below the stud 99 the lever 100 is bent laterally and then upwardly as shown in Fig. 10 to form a second arm 102 extending parallel to the arm 101. The arm 102 is formed with a vertical slot 103 for receiving the reduced end of an adjusting stud 105 which passes therethrough. The shouldered portion of the stud 105 abuts one side of the arm 102 and a nut 106 screwed onto the threaded extremity of the stud binds it in adjusted position in the slot 103. Surrounding the shank portion of the stud 105 is the looped end 107 of the plunger-rod 33, the loop being held in place by the head 108 of the stud. It will be readily understood that adjustment of the stud 105 in the slot 103 toward and away from the axis of the pivot-stud 99 will vary the eccentricity of the stud 105 with respect to the pivot and as the lever 100 is swung under the

pull of the link 66 the stud 105 will be rocked therewith to impart sliding movement to the plunger-rod 33.

The present drawings illustrate the improved tension-controlling means as arranged to operate a particular type of tension-device but it is to be understood that it may be used with various other types of tension-devices.

It will be observed from the foregoing that the present invention provides a particularly simple yet ingenious means for positively and accurately controlling the pressure on the tension-members during the winding of a package whereby to relieve the tension applied to the yarn as the linear speed of the latter increases. In this way the device operates automatically to maintain a substantially constant and uniform tension on the yarn from start to finish of the package.

As a particular feature of improvement in the present invention the tension-controlling device is operated directly from the winding mechanism in direct proportion to the growth of the package being wound without the use of interposed springs, weights or other unstable elements liable to cause vibration or chatter of the tension-elements and result in uneven tension being applied to the yarn. Furthermore, the improved tension-controlling device may be quickly and accurately adjusted to effect a range of action necessary to properly relieve the tension during the winding or like operation.

While the invention is herein shown and described as embodying several preferred forms of construction, it will be understood that other modifications may be made in the structure and arrangement of the parts of the device and in the method of applying it to use without departing from the spirit or scope of the invention. Therefore, without limiting myself in this respect, I claim:

1. A tension-device for winding and like machines comprising a member adapted to bear against a strand of yarn to resist its draft, resilient means acting against said tension-member, means acting against the resilient means to maintain it under compression, a rockable lever, an adjustable member fixed on the lever and rockable therewith as a unit, and a link connecting the member on said lever to act against the compression means, said adjustable member being movable on the lever for adjusting the connection of the link with the lever eccentrically of the pivot of said lever.

2. A tension-device for winding and like machines comprising a member adapted to bear against a strand of yarn to resist its draft, resilient means acting against said tension-member, means acting against the resilient means to maintain it under compression, a member rockable about a fixed pivot, an arm pivoted to the member at a distance from its pivot, a link connected to the arm at one end and connected at its opposite end to said compression means, and means for varying the position of the arm on the rockable member to adjust the end of the link eccentrically of the pivot of the rockable member.

3. A tension-device for winding and like machines comprising a member adapted to act against a strand of yarn to apply resistance to its draft, resilient means acting against said tension-member, means for maintaining said resilient means under compression, a rockable lever, a second lever pivoted to the first lever, means on the first lever engaging the second lever at a distance from its pivot to connect the two levers at spaced

- points, said last-named means being adapted to adjust the second lever angularly with respect to the first lever, and means connecting the second lever to the compression means.
5. A tension-device for winding and like machines comprising a member adapted to act against a strand of yarn to apply resistance to its draft, resilient means acting against said tension-member, means for maintaining said resilient means under compression, means adapted to shift said last-named means to vary the compression of the resilient means comprising a rockable lever, a second lever pivoted to the first lever, eccentric means connecting the two levers at a distance from their pivotal connection and adapted for adjusting the second lever relatively of the first lever, and means connecting the second lever with the compression means.
10. A tension-device for winding and like machines comprising a member adapted to act against a strand of yarn to apply resistance to its draft, resilient means acting against said member, means for maintaining said resilient means under compression, a pivoted lever, a second lever pivoted to the first lever, an eccentric rotatable on one lever and engaging the other lever at a distance from their pivotal connection and adapted to adjust the relationship of said levers, and means connecting the second lever with the compression means.
15. A tension-device, the combination of a member adapted to act on a strand of yarn to apply resistance to its draft, resilient means acting against said tension-member, means for maintaining said resilient means under compression, an element rockable about a fixed axis, a second element connected to and adjustable relatively of the first element, a link connecting the second element with the compression means, and eccentric means acting between the first element and second element for adjusting their relationship to vary the extent of movement of the link as said elements are rocked about the pivot of the first element.
20. A tension-device comprising a member adapted to apply resistance to a strand of yarn feeding thereacross, resilient means acting against said element, means for maintaining said resilient means under compression, a pivoted lever, a second lever pivoted to the first lever, one of said levers being provided with a slot, an eccentric on one lever engaging the slot in the other lever and operable to adjust the relationship of said levers, and means connecting the second lever with the compression means.
25. A tension-device comprising a member adapted to apply resistance to a strand of yarn feeding thereacross, resilient means acting on said tension-member, means for maintaining said resilient means under compression, a pivoted lever, a second lever pivoted to the first lever and formed with a slot at one side of its pivot, an eccentric on the first lever in frictional engagement with the sides of the slot in the second lever, means for rotating said eccentric to adjust the position of the second lever with respect to the first lever, and means connecting the second lever with the compression means.
30. A tension-device comprising means adapted to apply resistance to the draft of a yarn, resilient means acting against said tension means, means for maintaining said resilient means under compression, a rockable lever, a member pivoted to the lever and formed with resilient jaws at one side of its pivot, an eccentric on the lever fric-
- tionally engaged by the resilient jaws of said member, means for turning the eccentric to adjust the position of the member in relation to the lever, and a link connecting said member with the compression means.
35. In a winding machine, the combination of a winding-spindle and thread-guide adapted to recede one from the other during the winding of a package, a frame for movably supporting one of said elements, a pivoted member, a member movable on the pivoted member, a link directly connecting said pivoted member with the frame to adapt it to be rocked thereby, a tension-device for applying resistance to the draft of a yarn feeding to the package being wound, resilient means for actuating said tension-device, means for maintaining said resilient means under compression, a link connecting the member movable on the pivoted member with the compression means, and means for varying the position of the movable member on the pivoted member to adjust the connection of said last-named link on the movable member toward and away from the pivotal axis of the pivoted member.
40. In a winding machine, the combination of a winding-spindle, a thread-guide for traversing yarn on the spindle to wind a package, a traverse-frame for supporting the thread-guide to adapt it to recede from the winding-spindle, a tension-device for applying resistance to the draft of a yarn feeding to the package being wound, resilient means for actuating said tension-device, means for maintaining said resilient means under compression, a pivoted member connected directly to the traverse-frame to be rocked during the movement thereof, an adjusting member carried by said pivoted member, a link connecting said adjusting member with the compression means, and eccentric means for moving the adjusting member to adjust the link toward and away from the pivotal axis of the pivoted member.
45. In a winding machine, the combination of a winding-spindle, a thread-guide for traversing yarn on the spindle to wind a package, a traverse-frame for supporting the thread-guide to adapt it to recede from the winding-spindle, a tension-device comprising a member adapted to act against the yarn feeding to the package, resilient means acting against the tension-member, means for maintaining said resilient means under compression, a lever connected to be rocked by the traverse-frame during the recession of the thread-guide from the winding-spindle, a member pivoted to the lever, means on the lever engaging the member at a distance from their pivotal connection and adapted for adjusting the position of said member on the lever, and a link connecting said member with the compression means.
50. In a winding machine, the combination of a winding-spindle, a thread-guide for traversing yarn on the spindle to wind a package, a traverse-frame for supporting the thread-guide to adapt it to recede from the winding-spindle, a tension-device comprising a member adapted to act against the yarn feeding to the winding-spindle, resilient means acting against the tension-member, means for maintaining said resilient means under compression, a lever connected to be rocked by the traverse-frame during the recession of the thread-guide from the winding-spindle, a member pivoted to the lever, an eccentric connecting the member and lever at a distance from their pivotal connection and adapted for adjusting said member to various positions with

respect to the lever, and a link connecting said member with the compression means.

14. A tension-device for winding machines comprising a member adapted to bear against a strand of yarn to resist its draft, resilient means acting against said tension-member, means acting against the resilient means to maintain it under compression, a pivoted member, a member mov-

able on the pivoted member, a link connecting the movable member with the compression means, and an eccentric for adjusting the movable member on the pivoted member to vary the point of connection between the link and the movable member with respect to the pivotal axis of the pivoted member. 5

HAROLD WOOD HITCHCOCK.
